United States Patent Office.

OTTO BRÜCK, OF NEW YORK, N. Y.

Letters Patent No. 76,988, dated April 21, 1868.

IMPROVEMENT IN POCKET-BOOK AND FAN COMBINED.

The Schedule referred to in these Letters Patent and making part of the same.

TO ALL WHOM IT MAY CONCERN:

Be it known that I, OTTO BRÜCK, of the city, county, and State of New York, have invented a new and improved Pocket-Book and Fan Combined; and I do hereby declare the following to be a full, clear, and exact description thereof, which will enable those skilled in the art to make and use the same, reference being had to the accompanying drawing, forming part of this specification, in which drawing—

Figure 1 represents a front view of this invention when the fan is drawn out for use.

Figure 2 is a sectional front view when the fan is drawn in.

Similar letters indicate corresponding parts.

This invention consists in arranging, in the edge of a pocket-book, a fan, which can be drawn in or pulled out, in such a manner that a lady, carrying her pocket-book in her hand, is enabled to pull out the fan and fan herself, or to draw in the fan, and carry her pocket-book in the ordinary manner; and that a neat and convenient article is produced, which combines the advantages of a fan and of a pocket-book.

A represents a pocket-book or portemonnaie, made in any desirable form or shape, of morocco, or any material from which such articles are usually made.

In the edge of this pocket-book I secure a fan, B, which may be constructed of two telescopic tubes, as described in Letters Patent granted to me, November 19, 1867, or which may be constructed in any other suitable manner, so that it can be drawn in to the position shown in fig. 2, or pulled out to the position shown in fig. 1. When the fan is pulled out, the pocket-book forms the handle of the fan, and the person carrying such pocket-book is enabled to fan himself or herself in the same manner as with an ordinary fan, and, at the same time, the contents of the pocket-book can be reached without difficulty.

When the fan is drawn in, the pocket-book can be carried in the pocket like an ordinary pocket-book.

By these means an article is obtained which combines the qualities of an ordinary pocket-book with those of a fan, in such a manner that the use of either will not in the least interfere with the utility of the other.

Having thus described my invention, what I claim as new, and desire to secure by Letters Patent, is—

A fan and pocket-book combined, as a new article of manufacture.

OTTO BRÜCK.
